(57) **CLAIM**

The ornamental design for a card reading apparatus, as shown and described.

DESCRIPTION

FIG. 1 is a perspective view of a card reading apparatus;

FIG. 2 is a front plan view thereof;

FIG. 3 is a bottom elevational view thereof;

FIG. 4 is a right side elevational view thereof;

FIG. 5 is a top elevational view thereof;

FIG. 6 is a left side elevational view thereof; and,

FIG. 7 is a back plan view thereof.

The portions of the card reading apparatus illustrated in broken lines form no part of the claimed design.
